UNITED STATES PATENT OFFICE.

PATRICK CUMMINGS, OF NEWTON, MASSACHUSETTS, ASSIGNOR TO PATRICK J. CUMMINGS, OF SAME PLACE.

PADDLE-WHEEL.

SPECIFICATION forming part of Letters Patent No. 333,607, dated January 5, 1886.

Application filed July 16, 1885. Serial No. 171,785. (No model.)

To all whom it may concern:

Be it known that I, PATRICK CUMMINGS, of Newton, in the county of Middlesex, State of Massachusetts, have invented a certain new and useful Improvement in Paddle-Wheels, 5 of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved paddle-wheel; Fig. 2, a like view of the cam-plate detached; Fig. 3, a vertical transverse section of the plate shown in Fig. 2; Fig. 4, a side elevation of the head-stock detached; Fig. 5, an edge view of the same, and Fig. 6 a perspective view of one of the paddles or floats 20 detached.

Like letters of reference indicate corresponding parts in the different figures of the drawings.

My invention relates to that class of paddle-wheels which are provided with means for automatically feathering the paddles or floats; and it consists in a novel construction and arrangement of the parts, as hereinafter more fully set forth and claimed, the object being 30 to produce a simpler and more effective device of this character than is now in ordinary use.

The nature and operation of the improvement will be readily understood by all conversant with such matters from the following explanation, its extreme simplicity rendering an elaborate description unnecessary.

In the drawings, A represents the boat; B, the shaft; C, the cam-plate; D, the head-stock, 40 and E the paddles or floats, the boat and shaft being of the ordinary form and construction. The shaft is arranged horizontally in suitable bearings, and is designed to be driven or revolved by steam or otherwise in the usual manner. The cam-plate C is provided with a hole, m, for the shaft B, and is secured to the side of the boat A by the screws x, which pass through the holes d. Said plate is provided 45 on its outer face with two cams, f h, arranged in reverse or complementary order, the cam h

having its ends rounded as shown at r r, and the cam f as shown at t t. The head-stock D is secured to the end of the shaft outside of the plate C by means of the nut v, the end of the shaft being square, and fitted to enter a corresponding hole, l, in the stock, to prevent the stock from turning on the shaft. The paddles or floats E are arranged radially around the head-stock at equal distances apart, and journaled therein by means of the rods g, said rods 60 being inserted in holes i in said stock, and adapted to revolve axially. Two cross-bars, H J, are rigidly secured to each of the rods g at right angles thereto, and also to each other, the bars H being adapted to rest on the cam f when the paddle is in working position or not feathered, and the bars J on the cam h when not feathered, four elongated slots, y, being formed in the head-stock, into or through which the bars J project when the parts are 70 all in position for use, as shown in Fig. 1.

For convenience of description the paddles E in Fig. 1 have been respectively numbered 1, 2, 3, and 4.

In the use of my improvement, when the 75 shaft B is revolved in the direction of the arrow in Fig. 1, the inner end of bar H on the feathered paddle l will strike the curved end t of the cam f on the plate C, and turn said paddle half round, thus bringing it into the 80 position shown at 2, or so that it will strike the water flatwise. The shaft continuing to revolve, when it has reached position 3 the inner end of the bar J will strike the rounded or curved end r of the cam h, and cause the 85 paddle to make another half-revolution on its axis, thus feathering it, as it leaves the water, in a manner which will be readily obvious without a more explicit description. A semi-annual depression, z, is formed in the face of 90 the plate C, to prevent the bars J from engaging said plate when they are turned into parallelism with the shaft B, as shown in positions 2 and 3 in Fig. 1, a corresponding depression, b, being formed in said plate to prevent the bars H from engaging the same when turned into the positions 1 and 4 to feather the paddles. 95

Having thus explained my invention, what I claim is—

In a feathering paddle-wheel, a stationary plate provided with complementary annular cams, a shaft, a revolving head-stock on said shaft having slots near its periphery, and radial sockets intersecting said slots and extending through them toward the shaft, paddles having shanks occupying said sockets, and cross-bars on said shanks at right angles to each other adapted to be engaged by said an-

nular cams, the inner of said cross-bars operating within said slots and the other outside of the periphery of said head-stock, substantially as described.

PATRICK CUMMINGS.
